UNITED STATES PATENT OFFICE.

IRVING J. BALL, OF BROCK, NEBRASKA.

CORN-HARVESTER.

No. 834,245.

Specification of Letters Patent.

Patented Oct. 30, 1906.

Application filed May 31, 1905. Serial No. 263,132.

To all whom it may concern:

Be it known that I, IRVING J. BALL, a citizen of the United States, residing at Brock, in the county of Nemaha and State of Nebraska, have invented certain new and useful Improvements in Corn-Harvesters, of which the following is a specification, reference being had therein to the accompanying drawings.

10 This invention relates to machines for gathering and husking corn.

The novel characteristics of the present invention, as also the details in the construction and arrangement of the several parts of 15 a preferred embodiment of the invention, will be apparent from the detailed description hereinafter when read in connection with the accompanying drawings, forming part hereof, and wherein said embodiment is illustrated.

20 In the drawings, Figure 1 is a vertical longitudinal sectional view of so much of a machine as is necessary to a complete understanding of the present improvements, parts 25 being shown in elevation. Fig. 2 is a rear elevation, a couple of the guide-fingers O being broken away to show the flanges M of the carrier N and fingers k. Fig. 3 is a fragmentary perspective view of the cutters and their 30 immediately-associated parts, and Fig. 4 is a detail horizontal sectional view on a line through one of the vertical knife-blades.

Referring more specifically to the drawings, 35 wherein like reference characters refer to corresponding parts in the several views, A designates the frame of the machine, the same being adapted to be supported and adjusted upon traction and caster wheels, if desired. (Not shown.)

40 At the base of the machine and on opposite sides thereof are plates L, arranged, in conjunction with depending separated guide-fingers k and circumferential ribs or flanges M on the rotatable carrier N, to form ways K, 45 conveniently three in number, although a greater or less number may be employed, as may be found expedient under working conditions. The fingers k are pivotally supported by a fixed transversely-disposed plate 50 k', secured to the frame of the machine, and are rounded in a rearward direction at their lower ends to facilitate their travel over the ground, a spring L' being interposed between the fingers and the plate, exerting a 55 normal tension to press the fingers toward the ground. The ways just referred to are

for the purpose of guiding the stalks subsequent to the bending down of the same toward the ground, so that they will be presented in proper arrangement relative to the 60 other parts of the machine to be presently pointed out. It is to be noted that the guide-fingers k are directly beneath and in the vertical planes of the ribs or flanges M on the carrier N, Fig. 1, whereby to continually preserve the continuous guideways K without interfering with the rotation of said carrier. It is also to be observed that a plate L² above the forward ends of the ways K performs the function of pressing the 65 stalks downward toward the ground to prevent the teeth on the rotary carrier N from striking the ears on the stalk until the guide-fingers O now, to be defined, engage said stalks.

70 Arranged so that the spaces between the same may register with the ways K are a series of the guide-fingers O, the same having upwardly-turned oval-pointed ends, said fingers being secured in place for both lateral 75 and longitudinal adjustment in the following manner: P is a beam fixedly secured across the lower rear end of the machine and provided on its outer face with ribs p, designed to enter complementary grooves p' in the 80 upper face of each guide-finger O. This permits the proper adjustment of the fingers either in a lateral direction longitudinally of the ribs p or lengthwise of said fingers, as is 85 obvious. To lock the beam and fingers together, I provide bolts p² and nuts p³, said bolts passing through longitudinal slots p⁴ in the beam P and vertical slots p⁵, running longitudinally of the guide-fingers.

90 Q designates vertically-disposed knife-blades, the lower back edges of which are seated within depressions or recesses o in the upper surface of the guide-fingers O, the walls of the depressions preventing lateral play of the blades relative to the fingers and rivets 95 or pins o', passing through the blades and perforated ears o² on the fingers, serving to fasten the lower ends of said blades in their respective recesses or seats. The upper ends q of these blades Q are slotted, as at q', for 100 the reception of transversely-disposed bolts or pins q'', each connecting the free ends of a pair of bracket-arms q³ and bracing opposite sides of the blades and adjustable thereon and with said blades through the medium of 105 the slot-and-pin connection therebetween. Each pair of bracket-arms is connected by a 110

sleeve encompassing the shaft *s* and are held in proper position against lateral play on said shaft by means of a set-screw *r*.

A series of cutter-blades *R*, disposed transversely to and between the blades *Q*, are also loosely sleeved upon the shaft *s* at their upper edges and rest at their bottom edges upon the upper surfaces of the guide-fingers *O*, the same being locked in desired positions of lateral adjustment on the shaft by means of a slot-and-bolt connection *r'* between each of them and the beam *P*. The effective parts of these cutter-blades are of course those portions of the sharp edges thereof which are intermediate the guide-fingers and span the spaces therebetween. As shown, the cutter-blades incline upwardly and rearwardly relative to the guide-fingers. As the stalks pass through the ways *K* their attached or lower ends first enter the spaces between the guide-fingers and as the machine moves forward are drawn therethrough, whereby the ears are caught between the fingers and guided by the diverging walls thereof to the cutter-blades *R*, which cut the same from its butt and stalk when the detached ears are in position for the succeeding manipulation, as will presently appear.

The purpose of the knife-blades *Q* is principally to cut up and lessen the hindrance offered to the progressive movement of the machine by foreign matter or stalks disposed across the path of movement of said blades and transversely of the line of travel of the machine, also to keep the ears straight as they are cut from the stalks.

It is to be noted that the guide-fingers and transverse cutter-blades are designed to be arranged sufficiently close to the teeth *n* of the rotary carrier *N* to permit lengthwise entrance therebetween of the average large-sized ears, but too close to permit lengthwise turning or reversal of said ears, whereby I insure the travel of the separated ears butt first through the machine.

S is a toothed elevating or pusher roller for feeding the ears upwardly into the space between the rotary yieldably-pressed husking devices *T* and the carrier *N*, the second husking device being represented at *Y* and the teeth and plate for catching the husks carried around thereby at 2 and 3, respectively.

I is a caster-wheel, one being conveniently mounted at each side of the machine, and *W* an elevating device designed to raise the machine away from the ground and throw the weight thereof upon said caster when the machine is in the act of turning from a straight path.

The teeth of the husking devices *T* are cleaned partly by the teeth of the pusher-roller *S* and depending teeth *v*² on a supporting-plate *U*, while the husking device *Y* is cleaned by teeth *v*³ on a transversely-disposed rod *v*⁴ at the forward end of the ma-

chine. The teeth of the pusher-roller *S* are in turn cleaned by a stationary toothed rod *w*, situated behind a trash-roller *w'* and under the pusher-roller *S*. The rod just referred to has another series of teeth *w''* for cleaning the trash-roller, the whole arrangement being such as to effect the forcing of the husks or refuse backward beyond the bar *P* and rear ends of the fingers *O*. 70

It is to be understood that changes and alterations may be made in the machine above described and shown in the drawings without departing from the spirit of the invention. 75

Having thus described the invention, what is claimed as new, and desired to be secured by Letters Patent, is—

1. In a machine of the character described, guide-fingers, cutters on said fingers disposed in vertical planes, and a cutter in a plane at right angles to the said vertical planes and spanning the space between said first-named cutters, in combination with a rod extending transversely of the machine on which the spanning cutter is sleeved, and means for securing the spanning cutter in position. 80 85 90

2. In a machine of the character described, means for separating the ears from a stalk, and separated automatically - adjustable guiding-fingers for the stalks projecting downwardly and rearwardly relative to the direction of travel of the machine and toward the separating means forming a way leading to said separating means. 95

3. In a machine of the character described, means for separating the ears from a stalk, and separated pivoted guiding-fingers for the stalks projecting downwardly and rearwardly relative to the direction of travel of the machine and toward the separating means forming a way leading to said separating means. 100 105

4. In a machine of the character described, guide-fingers, cutters on said guide-fingers disposed in vertical planes, and a cutter in a plane at right angles to the said vertical planes and spanning the space between said first-named cutters, in combination with a rod extending transversely of the machine on which the spanning cutter is sleeved and adjustable, and means for securing the spanning cutter in position. 110 115

5. In a machine of the character described, means for separating the ears from their stalks, means for bending the stalks toward the ground and automatically - adjustable guiding-fingers arranged to separate and aline the stalks longitudinally of the machine prior to their presentment to said separating means. 120

6. In a machine of the character described, guide-fingers, cutters on said fingers disposed in vertical planes, and a cutter in a plane at right angles to the said vertical planes and spanning the space between said first-named cutters, in combination with a rod extending 125 130

transversely of the machine on which the spanning cutter is sleeved, and means for securing the spanning cutter in position including a bolt engaging the cutter, and a bar 5 engaged by said bolt.

7. In a machine of the character described, means for separating the ears from their stalks, means for bending the stalks toward the ground, and automatically - adjustable

10 guiding - fingers arranged to separate and aline the stalks longitudinally of the machine prior to their presentation to said separating means, in combination with husking means operatively associated with said separating 15 means.

8. In a machine of the character described, guide-fingers, cutters on said fingers disposed in vertical planes, and a cutter in a plane at right angles to the said vertical planes and 20 spanning the space between said first-named cutters, in combination with a rod extending transversely of the machine on which the spanning cutter is sleeved, means for securing the spanning cutter in position including a bolt engaging a slotted portion of the cutter, and a bar engaged by said bolt.

9. In a machine of the character described, means for separating the ears from their stalks, means for bending the stalks toward 30 the ground and automatically - adjustable guiding - fingers arranged to separate and aline the stalks longitudinally of the machine prior to their presentation to said separating means, in combination with husking means 35 operatively associated with said separating means, and a coöperating carrier and pusher for feeding the separated ears thereto.

10. In combination with a carrier, means for separating ears from its stalk, and for presenting them butt first to said carrier.

11. In combination with a carrier, means for separating ears from their stalks, and for presenting them butt first to said carrier, including a cutter-blade having an inclined up- 45 per face.

12. In a machine of the character described, means for separating the ears from a stalk comprising a cutter-bar, guide-fingers leading thereto, forwardly-extending knife-blades on the guide-fingers, and means for securing said blades in place including a bracket secured to the side thereof.

13. In a machine of the character described, means for separating the ears from a stalk comprising a cutter-bar, guide-fingers leading thereto, forwardly-extending knife-blades on the guide-fingers, and means for securing said blades in place including a bracket

secured to the side thereof by means of an adjustable slot-and-pin engagement. 60

14. In a machine of the character described, means for separating the ears from a stalk comprising a cutter-bar, guide-fingers leading thereto, forwardly-extending knife-blades on the guide-fingers, and means for securing said blades in place including a bracket embracing the opposite sides thereof and connected thereto by means of an adjustable slot-and-pin engagement. 65

15. In a machine of the character described, guide-fingers, a support therefor including means permitting their lateral adjustment, cutters on said guide-fingers disposed in vertical planes, a cutter spanning the space between the guide-fingers, arranged in a plane at right angles to the said vertical planes, and means for adjusting said spanning cutter including a rod extending transversely of the machine, and means sleeved upon and slideable lengthwise on said 80 rod and connected to the spanning cutter. 70

16. In a machine of the character described, means for separating ears from stalks, and guiding instrumentalities operatively associated with said separating means 85 including guiding-fingers, and means whereby said fingers may be adjusted both laterally and longitudinally.

17. In a machine of the character described, adjustable guiding-fingers, a laterally-adjustable cutter-blade operatively associated with said fingers spanning the space intermediate adjoining fingers and in close proximity to said fingers. 90

18. In a machine of the character described, guide-fingers, cutters on said fingers disposed in vertical planes, and a cutter spanning the space between said first-named cutters and occupying a plane at right angles to said vertical planes, in combination with 100 instrumentalities whereby the guide-fingers and the cutters may be adjusted in a direction transversely of the machine. 95

19. In a machine of the character described, guide-fingers, a cutter spanning the 105 space between said guide-fingers, and means for independently securing the guide-fingers and spanning cutter in adjusted positions transversely of the machine.

In testimony whereof I affix my signature in presence of two witnesses.
